UNITED STATES PATENT OFFICE

2,569,324

POKER CHIP STAND

Robert B. Moyer, Los Angeles, Calif.

Application July 15, 1946, Serial No. 683,687

5 Claims. (Cl. 211—49)

1

This invention relates to utility stands and more particularly to a multiple poker chip stand which may also be adapted as a condiment holder, display rack and dispensing device, or the like.

Prior art devices have been known in which storage racks are associated with stationary or rotatable stands into which such racks may be swung during a period of non-use. Moreover a large assortment of poker chip stands and equivalent devices exist for the purpose of storing poker chips or other articles in a convenient manner, usually in racks or stands designed for placement upon a playing table or similar location.

In all of the above and other conventional devices of roughly analogous purpose to that intended by the instant invention, none is known utilizing a central control mechanism which is actuatable by a single movement in one direction for the purpose of moving the storage racks uniformly outwardly from a place of confinement within the stand to a selected position of convenient use and vice versa. In the devices presently known it is necessary to actuate a mechanism in a first direction for the purpose of making the stored articles accessible and in a second direction for confining the racks and contained articles within their associated stands. Furthermore, none of the conventional devices intended to fulfill the general purposes of this invention embody comparable features of convenience, effectiveness and simplicity of design. All operations are also calculated to be extremely simple, smooth and uniform, but without detracting from a desired economy in the construction of the apparatus and the ready assembly of its parts either on a mass production basis or otherwise.

It is therefore an object of this invention to provide a storage device and/or display rack utilizing a single unidirectional manipulating means either for the purpose of making a plurality of various articles intended to be stored within any number of storage racks associated therewith readily accessible, or, optionally, storing and hiding them from view.

It is a further object of this invention to provide a stand of the character described incorporating storage racks of new and improved design.

It is another object to provide a utility stand of new and improved construction having simple manipulative mechanism for alternately but simultaneously enclosing a plurality of storage racks within the stand or turning said racks si-

multaneously outwardly from said stand for convenient access, use, replacement or display of articles intended for storage in said racks.

It is a further object to provide a new and improved utility rack associated with a new and improved operative mechanism by which any number of storage racks associated therewith may be releasably held in a desired position within the stand or pivoted outwardly in a convenient manner therefrom.

Another further object is to provide a novelty stand of the desired character in association with a new and improved unidirectional actuating and clutch mechanism.

It is a still further object to provide an apparatus of the character described associated with a new and improved impulse and momentum control means for any number of storage racks associated therewith.

A still further object is to provide a novel association of handle and cover means for the stand as well as for any number of storage spaces provided therein.

It is also an object to provide a new and improved storage rack construction including a mounting means for use in a utility stand of the character described.

It is another further object to provide a utility stand of new and improved construction which can be readily and economically manufactured and conveniently assembled or disassembled for repair or replacement of parts.

Yet another object is to provide a new and improved rotatable platform construction for use with a stand of the character described.

It is also an object to provide improvements upon mechanisms associated with prior art devices having a like purpose.

With these and other objects in view, the invention consists in the construction, arrangement and combination of the various parts of the apparatus whereby the objects contemplated are attained, as hereinafter set forth, pointed out in the appended claims and illustrated in the accompanying drawings.

In the drawings:

Figure 1 is a plan view of a poker chip stand embodying this invention.

Figure 2 is a view similar to Figure 1 but with the handle covers in an alternative position.

Figure 3 is a vertical sectional view on the line 3—3 of Figure 1.

Figure 4 is a plan sectional view on the line 4—4 of Figure 3.

Figure 5 is a detail view of the handle and

cover hinge construction taken on the line 5—5 of Figure 2.

Figure 6 is a detail view of the button clutch mechanism in an initial operative position.

Figure 7 is a vertical section on the line 7—7 of Figure 6.

Figure 8 is a view of the clutch mechanism of Figure 6 in a position of extreme clockwise rotation of the control button.

Figure 9 is a vertical sectional view similar to Figure 7 taken on the line 9—9 of Figure 8.

Figure 10 is a view of the clutch mechanism in an operative position subsequent to that illustrated in Figures 8 and 9.

Figure 11 is a fragmentary view similar to Figure 4 showing the racks or columns in a so-called "dead center" position of their links between their position as illustrated for the closed position in Figure 4 and that illustrated for the open position in Figure 12.

Figure 12 is a view similar to Figure 11 showing the columns in their outwardly extended open position.

Figure 13 is a vertical elevational view of a modified form of mounting for the stand.

In the drawings, a stand generally designated by the numeral 20 comprises the following stationary frame components: An upper, annular frame member 21, a lower substantially disk-like frame member 22, and a central frame portion 23 disposed between the upper and lower frame members. These three relatively stationary frame members are secured together by vertical bolts 24.

Extending vertically through the central frame member 23 is a vertical rotatable shaft 25 journalled at its upper end in the upper portion of the central frame member, as designated by the numeral 26. Keyed to the upper end of the shaft 25 is a clutch disc 27 which is turnable about a vertical axis within the upper end of the central frame member 23, and keyed to the lower end of the same shaft is a control disc 28 formed with equally spaced holes 29 around its outer margins corresponding in number and position to any number of columns or the like such as chip columns 30. These chip columns and the control disc may be operatively connected together by means of individual links 31 in a manner hereafter to be described.

The chip columns 30 are preferably formed with a bore 32 extending vertically substantially throughout the length of the columns and are further provided with a second smaller arcuate notch 33 at the bottom end thereof in a manner to form a lower shoulder or shelf 34 enabling a pile of articles, such as poker chips, to be stacked in the bore within the column in such a manner that they may be easily accessible for removal when the chip columns are disposed outwardly with respect to the frame as illustrated in Figure 12.

The columns 30 are pivoted at their upper extremities upon pins 35 and at their lower extremities upon other pins 36, each of the lower pins being preferably supported at their ends upon frictionless ball bearings 37. The links 31 may be formed with upturned ends 31a which may be journalled respectively in the control disc 28 and the lower ends of the columns. The ends of the links which are journalled in the columns are spaced circumferentially with respect to the axis of the pivot pins 36 as illustrated, for example, in Figure 4, where the columns are in their most inwardly disposed position within the

stand or, as illustrated in Figure 12, where the columns are in their most outwardly projected open position.

Ignoring for a moment the operation of the clutch mechanism illustrated in detail, especially in Figures 3, and 6 through 10, the mode of operation of the stand is as follows: A manually rotatable button 38 is drivingly connected with the shaft 25 when the button is rotated in a clockwise direction. This result is accomplished through a clutching mechanism which will be later described, so that upon an operator's giving the button an initial clockwise rotation, starting from the position of the parts as illustrated in Figure 4, the shaft 25, the control disc 28, the inner ends and the links 31 will be drawn in a clockwise direction, thereby giving the chip columns an initial impulse by virtue of which they begin to swing upon their pivot pins 35 and 36 in a counter-clockwise direction outwardly, as illustrated in Figure 11. Inasmuch as the columns, after being thus set in motion, will have some weight and momentum, they will continue to rotate in a counterclockwise direction so as to pass the dead center position of the links 31, illustrated in Figure 11 and assume their fully extended outward position, as illustrated in Figure 12. This continued swinging movement of the chip columns assumes, of course, that the button 38 has been released or at least does not retard the return or counter-clockwise rotation of the disc 28 which obviously must occur if the columns are to pass the dead center position of the links 31. Such a release of the button 38 is accomplished through the clutch mechanism between and associated with the button and the clutch disc 27 which will be described hereinafter.

If, after the columns are outwardly extended as in Figure 12, the button 38 is grasped and again turned initially in a clockwise direction in a similar manner as above, a swinging movement of the chip columns will begin but this time in a reversed or clockwise direction in which the columns will be carried past the dead center position, illustrated in Figure 11, and subsequently assume their position within the stand, as illustrated in Figure 4. In either case, the weight and momentum of their contents and/or the chip columns will readily carry them past the dead center position of the links.

In order to assure the completion of an arc of approximately 180° required to position the columns and therefore also, necessarily, the disc 28 at their inward and outward limits, the disc 28 must return from the position illustrated in Figure 11 at which it is in its limit of clockwise rotation to the position illustrated in Figures 4 or 12, at which it is in its limit of counter-clockwise rotation. For this purpose a leaf spring 40, for example, may be secured as by one of its ends to the central frame member 23 and at the other of its ends in a pin 41 secured to the upper face of the disc 28. The spring 40 is formed so as to normally urge the disc in a counter-clockwise direction, and in so doing obviously aids the momentum of the chip columns in their arcuate outward and inward movement so as to carry them easily past the dead center position of the links 31, said position being illustrated in Figure 11. A stop pin 42, or the like, secured in the frame at a predetermined position relative to a suitable abutment on the revolving parts limits the movement of the disc in its counter-clockwise rotation and thereby

establishes the ultimate inward and outward rest positions of the columns in either direction of their movement.

Referring now to the clutching mechanism between the button 38 and the upper end of the shaft 25, the clutch disc 27, which is cooperably disposed below the button, constitutes the driven clutch member. It is keyed at its center to the shaft 25 and is formed with a vertical arcuate slot 45 therethrough, as most clearly illustrated in dotted outline in Figures 6 and 8. Said disc 27 is also formed with a cylindrical pocket 46 disposed above and circumferentially aligned with the arcuate slot 45. The pocket 46 is designed to loosely receive a ball 50, as illustrated most clearly in Figures 3 and 7, and is preferably of a depth slightly in excess of one-half the diameter of the ball, so that the ball normally nestles down into the pocket for slightly over one-half its diameter and finds a lateral abutment against the normal surface provided by the side walls of the pocket. The button, which constitutes the driving clutch member, also contains a cylindrical recess 51 substantially corresponding in diameter and position to the pocket 46, but said recess 51 is of sufficient depth to entirely accommodate the ball 50 therein, as illustrated in Figures 9 and 10.

Fixedly anchored by its lower end in the central frame member 23 and projecting upwardly into the slot 45 so as to be freely movable therein when the button 38 and disc 27 are rotated with respect to the central frame member 23, is a key 52 having a slanted upper face 53 upon which the ball 50 may ride upwardly in a manner to remove the same from the lower pocket 46 and carry it into the recess 51 in the button as when the button has been turned in a clockwise direction to a sufficient extent. Said button is normally urged to a limit of counter-clockwise rotation by means of a coil spring 55 which is secured at one of its extremities to a portion 23a of the central frame member 23 and at the other of its extremities to a point 38a spaced from the center of the button.

From this construction of the clutching mechanism, it may be seen that upon initial clockwise rotation of the button, as illustrated, for example, in Figures 6 and 7, the ball 50 will rest in the pocket 46 while also projecting for somewhat less than one-half its diameter into the abutment formed by the recess 51, thereby the ball will be carried around with the button until the ball reaches the key whereupon it will be carried up over the slanted face 53 of the key and thence into the upper recess 51 in the button. At that point (see Figure 9) the disc 27, the shaft 25 and its associated control mechanism (which has also been simultaneously carried around in a clockwise direction by the clockwise rotation of the button) is free to return in a counter-clockwise direction, as urged by the momentum of the chip columns through the links and also by means of the spring 40, to a position determined by the mutual abutment of the stop pin 42 in the frame and the pin 41 on the disc.

It may be noted from the above description that it is desirable to retain the links and columns in constantly corresponding and equally spaced positions relative to one another. For this purpose, a preferably floating spacer may be provided, such as an annulus 60, for example, rotatably slidably upon and encircling the lower end of the central frame member 23. The spacer contains suitably spaced openings therein for the

spaced accommodation of each of the several links 31, thereby assuring that the operation of all the links will be uniform, simultaneous and in the same direction. Obviously, the columns 5 will also therefore be uniformly actuated and turned, whereas without such a suitable spacer the movement of the columns might be relatively chaotic and independent. Such a spacer, moreover, assists the movement as well as the retardation of movement of each column by the necessarily similar activation of every other column. Other equivalent forms of spacers, such as of stiff wire, etc., will readily occur to one skilled in the art of producing devices of this general character.

In addition, it may also be noted that the upper end of the stand is preferably formed with arcuate covers 65 which may serve as handles when pivoted upwardly upon hinges 66 as illustrated in Figure 2. A detail of the construction of the covers and their associated hinges appears in Figure 5 from which it may readily be seen that the handles are slotted at both ends to form rod-like pintles 70 rotatably confined within a suitably shaped bracket 71 which may be bolted or otherwise secured to the top frame member 21. When the covers 65 are elevated, as shown in Figure 2, the card pockets 68, intended for the storage of decks of playing cards or similar items, are revealed.

It is furthermore contemplated, as illustrated in Figure 13, that the entire stand may be mounted upon a relatively stationary circular platform 80 provided with a frictionless bearing assembly 81, so that the entire stand may be rotated as a unit whereby any side may face any selected direction.

Said platform 80 is formed with an upset central part 82 having on its lower side an access hole 83. Axially, the platform is secured to the lower frame member 22 by means of a bolt 84 adjustable to any desired degree of tightness through an adjusting nut 85. The tightening of this nut draws a round-shouldered head 86 of the bolt downwardly against a recessed abutment 87 in the center of the lower frame member 22, whereby the tendency of the frame 20 to rotate with greater or lesser friction independently of the platform 80 may be adjusted.

Around its periphery the lower frame member 22 may be formed with an independent flange 90 substantially covering the platform 80 around its external edge so that a pleasing appearance of an unbroken outline of the frame itself may be presented.

At the bottom of the frame in the embodiment of the invention illustrated in Figures 1 through 12, or at the bottom of the platform in the form illustrated in Figure 13, a suitable felt, rubber, 60 or other pad of soft, non-abrasive material 91 (or 100) may be applied for the obvious purpose of preventing injury to any polished surface upon which the stand may be placed.

It will therefore be seen that a stand of excellent appearance and construction adapted for the reception of any number of article-holding racks or columns has been provided in which a single control mechanism readily and smoothly operates to control any number of racks simultaneously.

It is not absolutely necessary in the practice of this invention that a clutch mechanism be employed, as described, but such a feature is eminently desirable and when used constitutes a valuable portion of the novelty and utility of the apparatus. Thus upon actuation of the con-

trof button in a single direction, the racks turn in a desired manner independently of the fact that the operator continues to retard the return movement of the button. Nor is it necessary to operate the button in two distinct directions for the purpose of turning the racks in alternate directions as was heretofore the custom. As herein described, the release and spring of the control button automatically returns to an initial position from which it may again initiate its rack or column-operating movement.

The entire apparatus has been devised so that it is readily producible by machine methods. For example, the links may be inserted in position with or without affixation to any other member except in a loose and easily replaceable manner. Each part is therefore adapted to be fabricated by means of regulation machine processes and the collective parts are further adapted to be assembled together in a superimposed, interfitting relationship upon the tightening of a few readily accessible bolts.

It is not intended to limit this invention by the use of any particular materials and while it is desirable in some cases to construct the frame and trays or columns and other external portions of the stand out of wood, these parts, as well as the shafts, discs, pins, and links, may be formed from any suitable material, such as metal, plastic, or the like; and the external parts may be covered with fabric or given any other desired finish.

It is the gist of this invention to provide a utility stand specially adapted for the storage of various articles which may be contained in any number of racks rotatably retractable for storage or rotatably extensible for convenient access, the holder being readily transportable, neat in appearance, solid in construction, and actuatable in a convenient and simple manner.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

The invention having been herein described, what is claimed and sought to be secured by Letters Patent is:

1. A utility stand comprising a frame, a weighted member pivotally mounted in the frame on a vertical axis, a link making a journalled connection at one of its ends with the weighted member at a point spaced from a first side of said vertical axis, control means associated with the other end of the link actuatable for initially drawing the link in a given direction from a starting position of the weighted member in a manner to give the weighted member an initial rotating movement in said direction, and resilient stop means for limiting the rotation of said weighted member in said direction when said one end of said link has been rotated therewith to a second side of said vertical axis, substantially opposite said first side, said resilient stop means being positioned between the frame and the control means in a manner to return the control means to said starting position such that similar actuations of the control means operate to draw said one end of said link around said vertical axis in alternately opposite directions.

2. A utility stand comprising a frame, a weighted member pivotally mounted in the

frame on a vertical axis, a link making a journalled connection at one of its ends with the weighted member at a point spaced from a first side of said vertical axis, control means associated with the other end of the link actuatable for initially drawing the link in a given direction from a starting position of the weighted member in a manner to give the weighted member an initial rotating movement in said direction, resilient stop means for limiting the rotation of said weighted member in said direction when said one end of said link has been rotated therewith to a second side of said vertical axis, substantially opposite said first side, said resilient stop means being positioned between the frame and the control means in a manner to return the control means to said starting position such that similar actuations of the control means operate to draw said one end of said link around said vertical axis in alternately opposite directions, and a clutch controlled manipulating means upon the control means adapted to slip after a predetermined interval in the movement of the manipulating means, whereby the resilient means

3. A utility stand comprising a frame, a weighted member pivotally mounted in the frame on a vertical axis, a link making a journalled connection at one of its ends with the weighted member at a point spaced from a first side of said vertical axis, control means associated with the other end of the link actuatable for initially drawing the link in a given direction from a starting position of the weighted member in a manner to give the weighted member an initial rotating movement in said direction, and resilient stop means for limiting the rotation of said weighted member in said direction when said one end of said link has been rotated therewith to a second side of said vertical axis, substantially opposite said first side, said resilient stop means comprising a relatively fixed abutment positioned in the frame, a movable abutment positioned on the control means and a spring anchored in the frame urging the abutment on the control means in a predetermined direction towards the relatively fixed abutment.

4. A utility stand comprising a frame, a weighted member pivotally mounted in the frame on a vertical axis, a link making a journalled connection at one of its ends with the weighted member at a point spaced from a first side of said vertical axis, control means associated with the other end of the link actuatable for initially drawing the link in a given direction from a starting position of the weighted member in a manner to give the weighted member an initial rotating movement in said direction, resilient stop means for limiting the rotation of said weighted member in said direction when said one end of said link has been rotated therewith to a second side of said vertical axis, substantially opposite said first side, said resilient stop means being positioned between the frame and the control means in a manner to return the control means to said starting position such that similar actuations of the control means operate to draw said one end of said link around said vertical axis in alternately opposite directions, and a clutch controlled manipulating means upon the control means adapted to slip after a predetermined interval in the movement of the manipulating means, whereby the resilient means

may operate to return the control means to said starting position independently of the manipulating means, said control means incorporating a rotatable actuating member secured to a driven clutch body, said manipulating means comprising a rotatable driving clutch body adjacent to and axially aligned with the driven clutch body, each of said bodies being formed with corresponding detents upon their adjacent faces, keying means normally associated with said detents for keying said bodies to one another, releasing means secured in the frame and adapted to release said keying means after a predetermined rotation of said bodies in a predetermined direction in a manner to free the driven body from its keyed connection with the driving body, and a second resilient means adapted to return said driving body to a starting position wherein the bodies are again drivingly connected together by said keying means.

5. A utility stand comprising a frame, a weighted member pivotally mounted in the frame on a vertical axis, a link making a journaled connection at one of its ends with the weighted member at a point spaced from a first side of said vertical axis, control means associated with the other end of the link actuatable for initially drawing the link in a given direction from a starting position of the weighted member in a manner to give the weighted member an initial rotating movement in said direction, resilient stop means for limiting the rotation of said weighted member in said direction when said one end of said link has been rotated therewith to a second side of said vertical axis substantially opposite said first side, said resilient stop means being positioned between the frame and the control means in a manner to return the control means to said starting position such that similar actuations of the control means operate to draw said one end of said link around said vertical axis in alternately opposite directions, and a clutch controlled manipulating means upon the control means adapted to slip after a predetermined interval in the movement of the manipulating means, whereby the resilient means may operate

to return the control means to said starting position independently of the manipulating means, said control means incorporating a rotatable shaft, a clutch plate axially secured to the shaft, a rotatable button axially aligned with the clutch plate, said plate and said button having adjacent faces each formed with a corresponding depression, one of said depressions being of greater depth than the other, a detent normally resident in the depression of lesser depth and extending into the depression of greater depth, thereby rotatably keying the button to the plate, said depression of lesser depth having an arcuate slot in communication therewith, a key formed with a slanting face secured in the frame and adapted to ride in the slot during an initial rotative movement of the button and further adapted to force the detent out of the depression of lesser depth into the depression of greater depth, said latter depression being sufficiently large to accommodate and release the button and plate for independent rotative movement, and a second resilient means adapted to return said driving body to a starting position wherein the bodies are again drivingly connected together by said keying means.

ROBERT B. MOYER.
